D. Harrington

Bath.

Patented Oct. 4, 1813.

The following referred to in these Letters Patent and making part of the same containing a description in the words of the said Daniel Hazzington himself of his warm bathing vessel. This warm bathing vessel is constructed with the bathing and the heating parts in one vessel, so as to occupy but little room, and be thereby better adapted to the use of families for which it is well calculated as relates to its simplicity of construction, cheapness, and the small quantity of fuel it will require for its intended purpose. The bathing and bathing parts may be separate if required and may be adapted to public bathing places as well as private, and may have any number of baths for either. This bathing vessel is constructed with a vessel of a box or cistern ~~which may be made of wood or any material that will hold water~~ may be made of wood or any material that will hold water, its form may be square, oblong or any other shape so the stone or furnace can be placed within it, if it may be used either with or without a top or lid, within this box or cistern is placed a stone or furnace which may be made of copper or iron, or any substance that will keep the fire and water apart, this stone or furnace is so placed that the water will surround it, or cover it on all its surface over its under side excepting so much of one end as must be necessarily be left to receive in the fuel and admit air. To this part of said end is attached a neck projecting from the end or main body of the stone or furnace a fire iron has two or three according to the size of the stone or furnace, the outer end of which neck is nicely let through either the end or side of the box or cistern which contains it, and made water proof by working or weaving through this said neck the fuel is put into the stone or furnace which contains a door to them or bridges to be pushed in, either which door must agree even with the end and main body of the said

stone or furnace, to prevent the fire from coming too near to the outer end of the neck which is let just through the end on side of the box or cistern and where box or cistern of wood of wood might otherwise take fire. On the top side (near the opposite end) or at the end of said box or cistern a pipe is attached and may take various directions within the box or cistern and convey the smoke out of the top, sides, bottom or any other part of said box. As the pipe as well as the upper part of the stone or furnace will be immersed in water or not according to the quantity put into the box. So the smoke may be conveyed from the said pipe into a chimney or through a wall or partition out of the place where the burning fuel stands. From the said box or cistern the warm or hot water is drawn through a cock at the end or sides into one or more places attached to it (or apart from it) as may be of a suitable form for a person to lay down at length or sit down and be in an easy posture. the best form is that of an oblong box sufficiently high in its sides & sufficiently wide & long to receive the person wishing to occupy it. so as he may be just immersed in the water excepting his head, but for the purpose of making as little water as possible to answer. the box may be made much narrower at the ends for the feet than that for the body. or it may be made rounding on its bottom. or it may be in an oblique form under where the neck and head would lay. and various other forms. The water is let out when done with through a hole by loosening a plug at the bottom. The aforesaid stone or furnace may be made in various forms so it has this neck of sufficient length attached to it at above described, and where said ^{neck} is attached to said stone or furnace it must be water tight as well as the whole of the stone or furnace and pipe and all the neck excepting its outer end.
